PROCESS FOR REFINING UNSATURATED HYDROCARBON MATERIAL WITH AN ALKALI OR ALKALINE EARTH METAL

Frank J. Soddy, Swarthmore, Pa., assignor to
The United Gas Improvement Company, a corporation of Pennsylvania

No Drawing. Application December 24, 1942,
Serial No. 470,078

9 Claims. (Cl. 260—677)

1

This invention relates to the purification of unsaturated hydrocarbons.

More particularly, this invention is concerned with the removal of certain impurities from unsaturated hydrocarbons, or mixtures thereof.

An object of the present invention is the removal of certain impurities from unsaturated hydrocarbons by the application of at least one finely divided metal of groups Ia and IIa of the periodic system, or active alloys thereof. Another object of the invention is the refining of olefines, or fractions or mixtures containing at least one olefine, under conditions designed to reduce the losses incurred in such operations. Other objects and advantages of the invention will be apparent to those skilled in the art upon an inspection of the specification and claims.

Unsaturated hydrocarbons and unsaturated hydrocarbon fractions, particularly those obtained by the pyrolysis of petroleum or of petroleum hydrocarbons, frequently contain substantial proportions of impurities which interfere with their use in most, if not all, industrial applications.

Thus, unsaturated hydrocarbons obtained by the pyrolysis of petroleum may contain impurities such as acetylenes, aldehydes, peroxides, phenolic compounds, other oxygen-containing compounds, sulfur-containing compounds, such as disulfides and mercaptans, nitrogen-containing compounds, and the like. These compounds may be present in proportions ranging from traces to several percent depending, among other things, upon the boiling range of the particular fraction or mixture in question, the characteristics of the petroleum or petroleum fraction from which it was obtained, and the cracking temperature, as well as other pyrolysis conditions, employed.

The removal of one or more impurities from unsaturated hydrocarbons or unsaturated hydrocarbon fractions is complicated generally by the ease with which such materials may be polymerized. The application of the refining techniques customarily employed for the removal of impurities from hydrocarbons or hydrocarbon fractions which are preponderantly saturated and/or aromatic in character, such as gasoline, kerosene, light petroleum distillates, coal tar fractions, and the like, to unsaturated hydrocarbons or unsaturated hydrocarbon fractions frequently leads to the conversion of a substantial proportion, or all, of such materials to inferior types of polymers.

As a result of extensive experimentation, I have discovered that unsaturated hydrocarbons and unsaturated hydrocarbon fractions and mixtures

2

may be refined by the application in finely divided form of at least one metal of group Ia and group IIa of the periodic table, as well as certain active alloys thereof. Particularly desirable results are obtained by the use of finely divided alkali and alkaline earth metals.

Examples of such metals are lithium, sodium, potassium, rubidium, caesium, barium, strontium and calcium. Due to the availability and low cost of sodium and potassium, however, these metals are preferred for the use set forth herein.

Alloys of these metals, such as NaPb_{10} , NaHg_4 , NaCas , NaZn_{12} , KNa , and the like, also may be employed for the removal of undesired impurities from unsaturated hydrocarbons. In general, the alloys of the respective metals react with the impurities present in such materials at a slower rate than the corresponding metals.

I find that a solution of sodium, or a suspension or emulsion of very finely divided sodium, or a solution, suspension, or emulsion of one or more sodium alloys or active compounds, is a particularly desirable agent for the removal of certain undesirable impurities from unsaturated hydrocarbons. Excellent results are obtained by the use of a suspension of very finely divided sodium.

The alkali metals, particularly sodium and potassium, are very active catalysts for the polymerization of unsaturated hydrocarbons. Thus, practically all of the early work on the preparation of synthetic rubber from isoprene, both in this country and abroad, was based on the use of sodium and/or potassium as the catalyst. Consequently, the use of such an active catalyst, particularly in finely divided (and hence most active) form, for the refining of unsaturated hydrocarbons would be expected to result in the conversion of the greater portion, if not all, of the unsaturated hydrocarbon to polymers.

It should be emphasized that the success of the refining operations is dependent upon rigid adherence to certain operating conditions such as temperature, reaction time, concentration, and so forth, which will be discussed in considerable detail.

Unsaturated hydrocarbons which may be refined by methods to be more particularly described herein include hydrocarbons containing at least one double bond such as olefines, for example, aliphatic, cyclic, and aromatic olefines; diolefines such as aliphatic, cyclic and aromatic diolefines; and mixtures containing one or more of the foregoing classes of hydrocarbons.

The process is particularly applicable to the refining of olefines, such as aliphatic olefines.

3

A desirable source of olefines to be refined by methods to be more particularly described herein is the by-product obtained upon the concentration of diolefines, such as butadiene. Thus, the olefine fraction obtained upon the concentration of a butadiene fraction usually contains substantial, and generally contains predominating, proportions of isobutylene. Such fractions may be refined readily by the process disclosed herein.

A preferred embodiment of this invention is the refining of isobutylene or of unsaturated hydrocarbon fractions in which isobutylene is the prepondering unsaturated hydrocarbon present. Such fractions also may contain minor proportions of one or more diolefines.

While the refining operations may be carried out in the absence of any added polymerization inhibitors, I prefer to employ one or more polymerization inhibitors in order to reduce the loss of the unsaturated hydrocarbons in the form of polymers, as well as to increase the limits of the permissible reaction variables.

Excellent results may be obtained when one or more inhibitors selected from a list comprising (1) secondary aryl amines such as phenyl beta-naphthylamine, diphenyl-p-phenylene diamine, isopropoxydiphenyl amine, aldol-alpha-naphthylamine (and polymers thereof), symm. di-beta-naphthyl-p-phenylene diamine, trimethyl dihydroquinoline (and polymers thereof), and the ditolylamines; (2) phenolic compounds, such as p-tertiary butyl catechol and alkylated polyhydroxy phenols; and (3) reaction products of a ketone, such as acetone, and/or an aldehyde, such as formaldehyde and acetaldehyde, with an amine, such as aniline, are used in the refining operations disclosed herein.

In general, I prefer to employ less than 10% by weight, of polymerization inhibitor, based on the unsaturated hydrocarbon or unsaturated hydrocarbon fraction in batch treating processes, and the maximum total volume of suspending liquid in the treating system at any one time in the case of continuous treating processes. Good results also have been obtained by the use of less than 5% inhibitor and even 2% inhibitor in certain cases, particularly when one or more of the inhibitors listed in the preceding paragraph are employed.

While the refining operations may be carried out in a satisfactory manner in a batchwise manner, I prefer to conduct such operations in a continuous or semi-continuous system in order to reduce the proportion of unsaturated hydrocarbon lost in the form of polymers, as well as to secure greater economy in the use of the reagent.

The preferred refining method disclosed herein differs fundamentally from all methods described heretofore for the refining of unsaturated hydrocarbons in that the material in question is treated with a metal of group IA or group IIA, or an active alloy of such metals, in finely divided or solution form in a continuous system preferably in the presence of one or more polymerization inhibitors. By the use of a continuous system, particularly in conjunction with the use of an inhibitor, the loss of unsaturated hydrocarbons due to side reactions or to polymerization is very markedly reduced, or almost completely eliminated.

Although the process may be carried out in any desired manner, I prefer to conduct it in a vertical vessel or tower in which a certain height of a liquid suspension or solution of the active refining agent is maintained. The material to

be refined then is passed upward through this column of liquid at a rate sufficient to insure the removal of the desired quantity and type of impurities present at the temperature employed.

Other methods of contacting the material to be treated and the refining agent also may be employed if desired. Thus, the unsaturated hydrocarbon may be passed through a horizontal treating unit, such as a pipe or bank of pipes, containing a suspension of the desired refining agent, or otherwise.

The suspending liquid employed for the refining agent may be of any desired type, provided that it does not react with the reagent or the material to be treated to any substantial extent, and provided that it does not introduce any additional impurities into the material to be treated. I find that hydrocarbons and hydrocarbon fractions are particularly desirable materials for use as suspending mediums for refining agents of the type described herein. Excellent results have been obtained by the use of aromatic hydrocarbons and aromatic hydrocarbon fractions for this purpose.

It is to be understood, of course, that the material to be treated may dissolve to some extent in the suspending medium, consequently the suspending medium actually employed in the operation of the process usually comprises a mixture of the material to be treated and the suspending medium initially introduced into the system.

The unsaturated hydrocarbon being treated also may serve as a suspending medium for the refining agent without the addition of any other material, if desired. Thus, the unsaturated hydrocarbon or unsaturated hydrocarbon fraction may be introduced into the desired tower or vessel, together with the finely divided refining agent, after which the material to be treated is passed into the suspension of the refining agent in the unsaturated hydrocarbon at the desired temperature, the charging rate and more particularly the operating pressure being adjusted to maintain the treating agent at the desired level in the vessel.

It is to be understood, of course, that the portion of the material to be treated which has been dissolved in the suspending medium or which has been employed as the suspending medium in the substantial absence of other liquid materials, does not necessarily remain in the treating zone throughout the entire treating cycle. Rather, this material is in a state of dynamic equilibrium with the material being treated, a portion of it volatilizing continuously and being removed from the system, the material volatilized in this manner being replaced by the solution of a corresponding quantity of freshly added material to be treated. The major portion of the material to be treated, of course, bubbles up through the suspending medium without dissolving therein.

The thickness of the layer of reagent through which the material to be treated is preferably passed depends upon a number of factors, such as the quantity and type of impurities present, the extent to which such impurities are to be removed, the type and degree of dispersion of the treating agent employed, the reaction temperature, the concentration of the treating agent in the suspending medium, and the like. In general, however, I prefer to employ a layer of reagent at least one foot thick and, more preferably, at least two feet thick. Excellent results

are obtained by the use of a layer of reagent at least four feet thick.

It will be recognized that, other things being equal, the depth of reagent employed in the treating vessel controls the contact time between the material to be refined and the refining reagent.

The degree of dispersion of the treating agent also has a very profound effect upon the degree of refining obtained. In the case of sodium, I prefer to employ a subdivided mass in which at least the majority of the particles present have a diameter of not more than 0.05" and, more preferably, not more than 0.03". Excellent results are obtained when at least the majority of the particles present have a diameter of not more than 0.02".

This subdivision may be carried out in any desired manner. Thus, in the case of sodium, a solution of this material in liquid ammonia may be introduced into an inert liquid, such as xylene, at room temperature or at elevated temperatures. The almost instantaneous volatilization of the ammonia present results in the dispersion of the sodium present in the xylene in an extremely finely divided state. Another method comprises spraying molten sodium into an inert liquid such as xylene or solvent naphtha. By suitable variations in the type and degree of fineness or in the dispersing ability of the spray nozzle employed, or both, sodium of almost any desired degree of fineness may be obtained at will.

Another satisfactory method comprises melting the sodium under the surface of a suitable liquid, such as xylene, followed by violent agitation, such as with a turbo-mixer, and cooling with agitation. Other methods which may be used include extrusion through fine orifices, and the generation of an arc between sodium electrodes in an inert liquid.

Although almost any desired concentration of treating agent in the suspending medium may be employed, depending upon the type and concentration of the unsaturated hydrocarbon in the diluted fraction to be refined, the temperature, the depth of reagent employed, and the like, I generally prefer to employ a reagent containing less than 30% and more particularly less than 20% by weight of the treating agent. Excellent results are obtained when less than 15% by weight of the treating agent is suspended in the suspending medium.

It is to be understood, of course, that the term suspending medium refers to the actual suspending agent employed during the treating operation, and includes any of the material being treated which may dissolve in such agent.

The concentration of the unsaturated hydrocarbon to be treated also has a considerable influence upon the method of operating the process. I generally prefer to employ such proportion of suspending medium that the actual concentration of the unsaturated hydrocarbon in the reaction zone is less than 80% and, more preferably, less than 70%. Excellent results are obtained when the actual concentration of unsaturated hydrocarbon in the reaction zone is less than 60%.

The process may be carried out at any desired pressure, such as atmospheric, subatmospheric, and superatmospheric pressures.

In many cases, particularly when a fairly highly concentrated fraction is refined with a suspension or solution of a finely divided active metal, or alloy of the type described herein, it is highly advantageous to conduct such operations

at subatmospheric pressures, thereby reducing the concentration of the unsaturated hydrocarbon present in the refining system at a given reaction temperature. This serves to reduce the quantity of unsaturated hydrocarbon converted to polymers in the process, consequently, it is a preferred embodiment of this invention.

The temperature at which the process is conducted also has a very considerable bearing upon the degree to which the unsaturated hydrocarbon is refined and the losses incurred due to polymerization. Although the optimum reaction temperature to be employed is dependent largely upon other factors, such as the concentration of both the unsaturated hydrocarbon and the refining agent in the reaction zone, I generally prefer to conduct the refining operations at temperatures below 100° C. and, more particularly, below 80° C. Excellent results are obtained by conducting the refining operations at temperatures below 70° C.

The rate at which the material to be refined is passed through the reagent has a very considerable effect upon the degree to which the impurities present are removed, although this is dependent to some extent upon other variables such as the concentration of refining agent in the suspending medium and the temperature at which the refining operations are being conducted. While it is difficult to establish exact limits for optimum throughputs under all conditions, I generally prefer not to exceed a throughput of material to be treated on an hourly basis of more than four times the weight of suspending medium employed and more preferably, not more than twice the weight of the suspending medium. Excellent results are obtained when not more than equal quantities of material to be treated, upon an hourly basis, are passed through the suspending medium.

It will be recognized that the contact time between the material to be treated and the reagent is determined both by the thickness of the layer of reagent employed and by the rate at which the material to be treated is passed through the reagent.

The method employed for introducing the material to be refined into the refining agent also has some influence upon the extent to which the unsaturated hydrocarbon or unsaturated hydrocarbon fraction is refined. In general, it may be said that a fine stream or jet of the liquid or gaseous material to be refined is desired. This may be accomplished by introducing the material to be treated into the reagent by means of suitable orifices, jets, nozzles, or other subdividing means. Porous objects or materials also may be employed for this purpose, such as porous ceramic or glass diffusing blocks or units.

As the refining agent may show some tendency to settle out in the bottom of the treating vessel or unit, the jets or nozzles by means of which the material to be treated is introduced into the unit may be so arranged as to prevent any undue settling of this material. In vertical vessels, this may be accomplished by locating these units in such a way as to impinge the inlet stream or streams upon the bottom of the treating vessel. The inlet jets also may be arranged tangentially to impart a swirling or circular motion to the treating reagent, if desired. Another method comprises locating the inlet jet or jets directly in the bottom of the reactor, or tangentially in the sides of the reactor, or both, to prevent any settling in the bottom of the reacting vessel and

to impart any desired circular or other motion to the treating medium.

Any desired combination of these methods also may be employed, such as the use of a jet or jets directly impinging upon the bottom of the reactor in conjunction with the use of a tangential jet or jets to prevent the active agent from settling out and depositing on the walls of the reactor and to maintain the reaction medium in any desired state of agitation.

The reaction medium also may be maintained in the desired degree of agitation by the use of suitable stirring or mixing devices, or by the use of circulating pumps, or by a combination of these methods, or otherwise. One or more of these methods also may be used in conjunction with one or more of the methods discussed previously to maintain the system in the desired degree of dispersion.

It should be pointed out, however, that the use of such agitation methods is not required in most cases. Thus, excellent results have been secured by conducting the refining operations in a tower, the material to be treated being introduced into the bottom of the tower by means of a small orifice. The passage of the fraction being treated in the gaseous state upward through the column usually is sufficient to maintain the system in the desired degree of agitation.

The refining agent, particularly when finely divided sodium is employed for this purpose, usually acts both as a reactant and as a polymerizing agent for the removal of undesired impurities. Thus, in the case of unsaturated hydrocarbons containing acetylenes, aldehydes, and other impurities, the sodium usually will react with at least a portion of the acetylenes present to form sodium acetyldes, and may react with certain of the oxygenated derivatives to form corresponding metallic derivatives. At least a portion of the acetylenic hydrocarbons present also are polymerized to form polymers, or copolymers with other unsaturated hydrocarbons present, which polymers frequently are insoluble in nature. Certain of the oxygenated derivatives, such as aldehydes, also may be polymerized to form polymers which may be insoluble in type.

As a result, the refining of unsaturated hydrocarbons with a suspension of finely divided sodium usually is characterized by the gradual accumulation of insoluble polymers in the refining medium. This may be removed in any desired manner, such as by filtration, which may be carried out continuously during the refining operation, or may be carried out in a batchwise manner after the termination of the refining step.

As the removal of the insoluble polymers also is attended by some loss or refining agent, even when the latter is in a very fine state of subdivision, it is advisable in many cases to continue the refining operations until the refining agent has been largely or completely exhausted before filtering.

The solid or semi-solid filtered products may be treated to recover any desired materials or they may be disposed of in any suitable manner. Thus, any unchanged refining agent, such as sodium, may be recovered by melting and coalescing operations, or by amalgamation with mercury, or otherwise. Certain of the reaction products, such as sodium acetyldes, may be decomposed with water to regenerate the corresponding acids or they may be reacted with

carbon dioxide to form unsaturated acids, or otherwise.

A convenient method for the disposal of the insoluble polymers comprises treatment with carbon dioxide, suitably in the presence of traces of moisture, followed by filtration.

As the cost of the treating process is largely a function of the quantity of the reactive agent employed in the refining operations, the efficient utilization of such agent is of considerable importance. A desirable method for insuring optimum utilization of the treating agent is to carry out the operations in a continuous countercurrent manner, the reagent moving through the system in a manner countercurrent to that of the material to be treated.

This may be illustrated by means of a consideration of a simple continuous countercurrent system comprising two treating towers or vessels. The material to be treated is passed into the first tower, which contains a partially exhausted reagent. This serves to remove a substantial portion of the impurities present, after which the partially refined material passes into the second tower, which contains a fresh, or more highly concentrated, reagent. This serves to remove the impurities present to the desired extent. The process is continued until the reagent in the first tower is almost, or completely, exhausted, after which it is discarded and the partially exhausted reagent from the second column substituted for it. Fresh reagent then is added to the second column.

In this manner the material to be treated and the treating agent pass through the system countercurrent to each other, the first continuously and the second in a discontinuous manner.

This may be modified such as by the continuous addition of fresh reagent to the second tower, the continuous transfer of partially exhausted reagent to the first tower, and the continuous withdrawal of more completely exhausted, or exhausted, reagent from the first tower. A completely continuous countercurrent treating system thus is achieved.

Any desired modification of these methods may be employed, and any number of treating towers or units may be used. It will be observed that in each of the cases discussed, the incoming material to be refined is contacted with partially exhausted reagent (maximum concentration of impurities—minimum concentration of reagent), while the outgoing material to be refined is contacted with fresh or more highly concentrated reagent (minimum concentration of impurities—maximum concentration of reagent). Thus the two objectives to be sought, namely, practically complete, or complete, utilization of the reagent and substantial, or practically complete, removal of impurities from the material to be refined, are achieved.

As the limiting factor affecting the utilization of the reagent is the proportion of insoluble polymers and/or residues which can be contained therein without seriously impairing its flowing properties, or the passage of the gaseous material to be treated therethrough, it frequently happens that the quantity of insoluble material present is insufficient to interfere seriously with the operation of the process when the refining agent present has been almost completely exhausted. In this case, the operation of the unit may be continued by the addition thereto of an additional quantity of the refining agent, and this process may be continued until the concen-

tration of insoluble material in the reagent renders it too viscous to be used further in the process in a satisfactory manner.

In this connection, it is well to point out that the insoluble products formed during the reaction have a tendency to stabilize the sodium suspension and act to reduce the rate of settling of the finely divided sodium in certain cases. As this is desirable, the incomplete removal of insoluble products from the reagent may be indicated, or even the addition of a certain quantity of such materials to a fresh reagent.

Soluble polymers also usually are formed in small amounts during the refining operations. As certain of these soluble polymers are converted on prolonged contact with the refining agent to viscous or insoluble products, their removal from the suspending medium, suitable at the end of a refining cycle and prior to the return of the suspending agent to the system, may be indicated. On the other hand, certain of these soluble polymers are sufficiently stable to act as a suspending medium for the refining agent.

An example of procedure which may be conveniently followed in the practice of my invention is as follows:

Example 1

A light oil fraction containing approximately 25% isobutylene, as well as approximately 1% acetylenic hydrocarbons, 0.05% aldehydes, and other impurities, was passed continuously in the gaseous state into a xylene suspension of finely divided sodium contained in a steel column 2" in diameter at a temperature of 50° C.

Under the operating conditions chosen, the refining agent comprised a 10% suspension of finely divided sodium in a suspending medium containing approximately 90% xylene and 10% isobutylene fraction. The height of refining agent employed was approximately 6 feet.

The refining operation was continued for a period of 30 hours, the isobutylene fraction being charged at the rate of approximately 1000 grams per hour.

The product obtained was water-white in color and contained only 0.002% acetylenes. The aldehydes present had been removed completely. The product was in a high state of purity and could be used for the production of polybutene or synthetic rubber, suitably by copolymerization with relatively small proportions of one or more diolefines.

In the specification and in the claims, the following terms have the indicated meanings.

The term "a metal of group IA and group IIA of the periodic system" is intended to mean one of a group consisting of lithium, sodium, potassium, rubidium, caesium, barium, strontium, and calcium.

The term "alkali metal" is employed as definitive of the group of metals consisting of lithium, sodium, potassium, rubidium, and caesium.

The term "finely divided" is intended to mean a material reduced to such a state of fineness that the preponderating part is composed of particles having a diameter of less than 0.05", as well as materials in the colloidal or dissolved form.

While reagents and procedures of a particular nature have been specifically described, it is to be understood that these are given by way of illustration. Therefore, changes, omissions, additions, substitutions, and/or modifications may be made within the scope of the claims without departing from the spirit of the invention.

I claim:

1. A process for refining unsaturated hydrocarbon material having from one to two double bonds per molecule, said unsaturated hydrocarbon material being contaminated with impurity including acetylenic and aldehyde material, comprising passing said unsaturated hydrocarbon material at a temperature below 100° C. through a dispersion of a finely divided material selected from the group consisting of metals of group IA and group IIA of the periodic system and alloys thereof, said dispersion being at least one foot in thickness in the direction of flow of said unsaturated hydrocarbon material and containing less than 30% by weight of said finely divided material, maintaining the concentration of said unsaturated hydrocarbon material in the reaction zone below 80% by weight of the total material present, while maintaining the rate of flow per hour of said unsaturated hydrocarbon material through said dispersion at less than four times the weight of dispersion medium employed, and removing said unsaturated hydrocarbon material less contaminated with impurity including acetylenic and aldehyde material from said reaction zone sufficiently rapidly to prevent a large loss of said unsaturated hydrocarbon material due to the polymerization thereof.

2. A process for refining unsaturated hydrocarbon material having from one to two double bonds per molecule, said unsaturated hydrocarbon material being contaminated with impurity including acetylenic material, which comprises continuously passing said unsaturated hydrocarbon material at a temperature below 80° C. through a dispersion of a finely divided material selected from the group consisting of metals of group IA and group IIA of the periodic system and alloys thereof, said dispersion containing less than 20% by weight thereof of said finely divided material and being at least two feet in thickness in the direction of flow of said unsaturated hydrocarbon material, maintaining the concentration of said unsaturated hydrocarbon material in the reaction zone less than 70% by weight of the total material present, while maintaining a rate of flow per hour of said unsaturated hydrocarbon material through said dispersion of less than twice the weight of dispersion medium employed, and continuously removing said unsaturated hydrocarbon material less contaminated with impurity including acetylenic material from said reaction zone sufficiently rapidly to prevent a large loss of said unsaturated hydrocarbon material due to polymerization thereof.

3. A process for refining unsaturated hydrocarbon material having from one to two double bonds per molecule, said unsaturated hydrocarbon material being contaminated with impurity including aldehyde material, which comprises continuously passing said unsaturated hydrocarbon material at a temperature below 80° C. through a dispersion of a finely divided material selected from the group consisting of metals of group IA and group IIA of the periodic system and alloys thereof, said dispersion containing less than 20% by weight thereof of said finely divided material and being at least two feet in thickness in the direction of flow of said unsaturated hydrocarbon material, maintaining the concentration of said unsaturated hydrocarbon material in the reaction zone less than 70% by weight of the total material present, while maintaining a rate of flow per hour of said unsaturated hydrocarbon material through said dispersion of less than twice the

11

weight of dispersion medium employed, and continuously removing said unsaturated hydrocarbon material less contaminated with impurity including aldehyde material from said reaction zone sufficiently rapidly to prevent a large loss of said unsaturated hydrocarbon material due to polymerization thereof.

4. A process for refining olefine material contained in a mixture including acetylenic material, which comprises continuously passing said mixture in vapor phase under temperature conditions below 100° C. through a dispersion of a finely divided alkali metal, said dispersion containing less than 30% by weight thereof of said finely divided alkali metal and being at least one foot in thickness in the direction of flow of said mixture, maintaining the concentration of said olefine material in the reaction zone less than 80% by weight of the total material present, while maintaining the rate of flow per hour of said mixture through said dispersion at less than four times the weight of dispersion medium employed, and continuously removing said olefine material less contaminated with impurity including acetylenic material from said reaction zone sufficiently rapidly to prevent a large loss of said olefine material due to polymerization thereof.

5. A process for the recovery of aliphatic olefine material from a mixture containing the same and containing impurity including acetylenic material, which comprises continuously passing said mixture in vapor phase under temperature conditions below 80° C. through a dispersion of finely divided sodium, said dispersion containing less than 20% by weight thereof of said finely divided sodium and being at least two feet in thickness in the direction of flow of said mixture, maintaining the concentration of aliphatic olefine material in the reaction zone less than 70% by weight of the total material present, while maintaining a rate of flow per hour of said mixture through said dispersion of less than twice the weight of dispersion medium employed, and continuously removing said aliphatic olefine material in vapor phase less contaminated with impurity including acetylenic material from said reaction zone sufficiently rapidly to prevent a large loss of said aliphatic olefine material due to polymerization thereof.

6. A process for the purification of aliphatic olefine material contained in admixture with impurity including aldehyde material, which comprises continuously passing said admixture in vapor phase at a temperature below 80° C. through a reaction zone containing a dispersion of finely divided sodium, said dispersion containing less than 20% by weight thereof of said finely divided sodium and being at least two feet in thickness in the direction of flow of said admixture, maintaining the concentration of aliphatic olefine material in said reaction zone less than 70% by weight of the total material present, while maintaining a rate of flow per hour of said admixture through said dispersion of less than twice the weight of dispersion medium employed, and continuously removing said aliphatic olefine material in vapor phase less contaminated with impurity including aldehyde material from said reaction zone sufficiently rapidly to prevent a large

12

loss of aliphatic olefine material due to polymerization thereof.

7. A process for the purification of isobutylene contained in admixture with impurity including acetylenic material, which comprises continuously passing said admixture in vapor phase at a temperature below 100° C. through a dispersion of finely divided sodium, said dispersion being at least one foot in thickness in the direction of flow of said admixture and containing less than 30% by weight thereof of said finely divided sodium, maintaining the concentration of said isobutylene in the reaction zone less than 80% by weight of the total material present, while maintaining the rate of flow per hour of said admixture through said dispersion at less than four times the weight of dispersion medium employed, and continuously removing isobutylene in vapor phase less contaminated with said impurity including acetylenic material from said reaction zone sufficiently rapidly to prevent a large loss of said isobutylene due to polymerization thereof.

8. A process for the recovery of isobutylene from a mixture containing the same and containing impurity including acetylenic material, which comprises continuously passing said mixture in vapor phase at a temperature below 70° C. through a reaction zone containing a dispersion of finely divided sodium at least the majority of the particles of which have a diameter of not more than 0.05", said dispersion containing less than 30% by weight thereof of said finely divided sodium and being at least one foot in thickness in the direction of flow of said mixture, maintaining the concentration of said isobutylene in said reaction zone less than 80% by weight of the total material present, while maintaining a rate of flow per hour of said mixture through said dispersion of less than four times the weight of dispersion medium employed, and continuously removing isobutylene in vapor phase and less contaminated with said impurity including acetylenic material from said reaction zone sufficiently rapidly to prevent a large loss of said isobutylene due to polymerization thereof.

9. A process for the purification of a light oil isobutylene fraction containing isobutylene together with impurity at least a portion of which is in the form of acetylenic material, which comprises continuously passing said fraction in vapor phase at a temperature below 80° C. upwardly through a reaction zone containing a dispersion of finely divided sodium at least the majority of the particles of which have a diameter of not more than 0.03", said dispersion containing less than 20% by weight thereof of said finely divided sodium and being at least two feet in thickness in the direction of flow of said fraction, maintaining the concentration of said isobutylene in said reaction zone less than 70% by weight of the total material present while maintaining a rate of flow per hour of said fraction through said dispersion of less than twice the weight of dispersion medium employed, and continuously removing said fraction in vapor phase from the top of said reaction zone less contaminated with impurity including acetylenic material sufficiently rapidly to prevent a large loss of said isobutylene due to polymerization thereof.
